Fig. 3.

Fig. 4.

To all whom it may concern:

Be it known that I, Arthur D. Altemiller, a citizen of the United States, residing at Affton, St. Louis County, State of Missouri, have invented a new, original, and ornamental Design for a Counter Food Warmer Casing, of which the following is a specification, reference being had to the accompanying drawing forming a part thereof, in which:

Figure 1 is a perspective view of the front, top and one side of a counter food warmer casing, embodying my new design;

Figure 2 is a top plan view thereof;

Figure 3 is a front elevational view thereof; and

Figure 4 is a side elevational view thereof.

Figures 2, 3 and 4 are shown on a reduced scale.

The other side is like the side shown, and the rear is a plain unornamented wall.

I claim:

The ornamental design for a counter food warmer casing, substantially as shown and described.
